APPARATUS FOR DISPERSING GASES IN LIQUIDS

Filed Oct. 18, 1946

UNITED STATES PATENT OFFICE

2,448,590

APPARATUS FOR DISPERSING GASES
IN LIQUIDS

Roland E. Gunther, Oceanside, N. Y.

Application October 18, 1946, Serial No. 704,236.

4 Claims. (Cl. 261—93)

1

This invention relates to apparatus and methods for effecting gas and liquid contact, and more particularly to apparatus for dispersing gases in liquids, employing porous media submerged in the liquids.

In attempting to create fine dispersions of gases in liquids, by forcing the gases through porous media submerged in the liquids, it has been discovered that the gases as they emerge from the porous media encounter resistance to their progress away from the media due to the viscosity or/and internal friction of the liquids and, consequently, remain at the exits momentarily until bubbles are formed of sufficient size to overcome this viscosity or/and friction, so that the fine dispersions sought for are not obtained.

An important object of the invention is to provide an apparatus for effecting the fine dispersion of gases in liquids, employing a submerged porous media, wherein the emerging gases are swept away from the exits of the media in streams of minute bubbles.

Other objects and advantages of the invention will be apparent during the following detailed description of the invention, taken in connection with the accompanying drawing, and in which drawing—

Figure 1 is an elevation of the novel apparatus.

Figure 2 is a vertical section through the porous media-carrying portion thereof.

Figure 3 is a bottom plan of the portion of Figure 2.

Figure 4 is a plan view of the inner face of the uppermost section of the portion of Figure 2.

Figure 5 is a plan view of the inner face of the lowermost section of the portion of Figure 2.

Figure 6 is a vertical section through a support forming the upper part of the novel apparatus.

In the drawing, wherein for the purpose of illustration is shown a preferred embodiment of the invention and wherein similar reference characters designate corresponding parts throughout the several views, the novel apparatus is designated as A and a porous media as B.

The novel apparatus A is shown to include a support 10, a gas-carrying conduit 11 extending thereto, a shaft 12 journaled in the support 10, means 13 to rotate the shaft 12, and means 14 to rotatably support the porous media B and effect rapid separation of minute gas bubbles formed at the outer surface of the porous media B.

Any suitable support may be provided. In the example shown, particularly in Figures 1 and 6,

5 the support 10 is a hollow coupling member 15 having an interiorly screw threaded, gas intake mouth portion 16 leading to a chamber 17 and from which chamber leads a gas exit portion 18 which may be exteriorly screw threaded. Supporting a ball bearing race 19 within the gas exit portion 18 may be a cap portion 20 having an upwardly-extending, circular flange 21 provided with screw threads and a horizontally-disposed, centrally-perforated disc-like portion 22 from which the flange 21 extends. The screw threads of the flange 21 are constructed and arranged to cooperate with those of the gas exit portion.

Coupled to the intake mouth portion 15 is the gas-carrying conduit 11 which extends to the gas supply (not shown).

The shaft 12 is hollow, open at both ends, and may have a flange 23 at its upper end disposed upon and suitably secured to the inner section of the ball race 19. It depends from the support and may be screw threaded at its lower end for cooperation with screw threads of the means 14 to be described.

For rotating the shaft, the means 13 may include any suitable device, such as an electric motor 24, to the shaft of which is secured a gear wheel 25, the teeth of which mesh with the teeth of a gear wheel 26, extending about and secured to the shaft 12. A suitable bracket 27 may be provided, securing the motor 24 to the support 10.

The means 14 shown particularly in Figures 2 to 5 inclusive includes a housing 28, shown particularly in Figures 2 and 4, defining a compartment, a gas inlet or mouth 29 and a gas exit 30. The housing may comprise a disc-like portion 31 and a skirt portion 32 with the disc-like portion 31 provided with the gas inlet 29 from the edge of which inlet projects an upwardly-extending flange 33 and this may be screw threaded to receive a screw threaded coupling member 34 for connection with the screw threaded lower end of the shaft 12. Extending through the disc-like portion 31 may be a suitable number of screw shank-receiving openings 35 for a purpose to be described.

Carried by the housing 27 for rotation by the shaft 12, as the latter rotates, the housing, is impeller means which also functions, in a dual capacity, to support the porous media B.

The impeller means, shown more particularly in Figures 2, 3 and 5 includes an inverted dome-like portion 36, impeller blade portions 37 carried thereby and a second inverted dome-like portion 38, carried by the blade portions 37.

Referring to Figures 2 and 5, it will be seen that the first inverted dome-like portion 36 has a shallow skirt section 39 extending upwardly from the periphery of a central section 40 and with its outer face convex. In fact this section 39 should be only deep enough to prevent side-way movement of a suitable gasket 41 and permit the gasket to extend slightly upwardly beyond the horizontal plane of the upper edge of the skirt section 39. The central section 40 of the dome-like portion 36 has, of course, a curved lower face adjacent its rim, as in Figure 2, and is provided with a downwardly extending, axially-disposed boss 42 for supporting the inner ends of the blade portions 37. Extending through the section 40 are a plurality of screw threaded openings 43 for receiving the shanks of cap screws 44 which also extend through the openings 35 in the disc-like portion 31, with their heads bearing against the upper face of the portion 31.

As may be seen in Figure 3, there is provided a plurality of impeller blade portions 37, extending outwardly from the boss 42 and downwardly from the lower face of the dome-like portion 36. Their free outer edges are substantially vertical and extend downwardly from the skirt section 39.

Referring to Figures 2 and 3, it will be seen that the second inverted dome-like portion 38 is quite dished or bowed, has an outwardly-extending, narrow, peripheral flange 45 and a large central opening 46. Preferably, this opening 46 has a diameter of a length substantially one-half that of the portion 38. The outer edge of the flange 45 is preferably, in substantially the same vertical plane as that of the outer face of the skirt portion 32. Portions of the lower edges 47 of the impeller blades 37 extend to and are suitably secured to the second inverted dome-like portion 38, whereby the portions 31, 32 and 38, together with the blades 37 rotate as a unit. The remaining portions of the lower edges 47 of the blades 37 extend across the central opening 46 from the boss 42.

The porous media B may be any suitable material (adapted, when compacted, to form minute passageways), compacted into a cake or body 50 of ring-shape having substantially flat upper and lower faces 51 and 52 respectively, an outer periphery 53 and a central opening 54. This cake 50 is disposed upon the impeller means structure and housed snugly within the housing 28, substantially as shown in Figure 2. So disposed, the outer section of the lower face of the cake 50 faces, but is spaced from, the upper edge of the skirt section 39, extends beyond the outer edges of the blades 37 and has the remainder of its lower face in tight contact with the gasket 40, so that there is a portion of the cake 50 extending outwardly of the vertical plane of the periphery of the gasket 40.

With the cake 50 in place and the cap screws tightened, it is clear, from Figure 2, that gases flowing downwardly through the hollow shaft 12 will enter the compartment defined by the inner face of the ring-shaped cake 50, parts of the upper face of the dome-like portion 37, and lower face of the disc-like portion 31, and inner face of the gasket 40. The gases can emerge only after passing through the porous media B and exit from the exposed lower face 52 of the cake 50. As the gases exit they will form minute bubbles. Before the bubbles can become larger they will be detached and swept from this exposed lower face 52 by the current created by

the rotating impeller blades 37 in the liquid in which the means 14 is immersed.

Of course, the relatively large opening 46 causes a considerable volume of liquid to rush therethrough, in the wake of the rotating impeller blades. This liquid is forced against the arcuate upper face of the second dome-like portion 38 and arcuate lower face of the first dome-like portion 36 and emerges with considerable force from the narrow opening formed by the flanges 45 and lower edge of the skirt portion 32 drawing the bubbles of gas along and outwardly of the means 14, for dispersement in the liquid.

In addition to the positive detachment of the gas bubbles, effected as stated, there is provided an efficient supplemental detachment resulting from the rotation of the cake 50 itself since the bubbles will be brushed from the rotating cake by the liquid body.

In Figure 3 the motion of the liquid with respect to the means 14 as a whole is shown by the arrows marked B. The liquid, therefore, moves radially away from the means 14 and tends to carry away therefrom any gases emerging from the openings in the porous cake 50. In addition to this positive radial movement, is that caused by the rotation of the cake itself and this is also one between the liquid and exits of the gas from the cake 50. This latter movement is indicated by the arrow marked C, extending non-radially with respect to the axis of rotation of the means 14. The magnitude of this latter movement can be made very great with little consumption of power. The resultant relative movement caused by the motions described and indicated is indicated by the arrow D, and this is also great. By virtue of the Bernouille principle, the pressure at the liquid contact surface of the porous cake 50 is substantially lower than in the remainder of the liquid and also because of the high relative velocity between the porous piece and the liquid at that point.

It is now obvious that the gas may be forced through a porous media cake or body while the latter is being rotated and in contact with a liquid, with the gas taking a generally downward course, to exit from the uncovered lower end of the cake to form fine bubbles, which are then quickly and continuously swept or forced away from the cake by the liquid, under forced upward and outward flow, impelled by impeller blades, so that larger-sized bubbles do not form.

Various changes may be made to the form of the invention herein shown and described without departing from the spirit of the invention or scope of the claims.

What is claimed is:

1. In gas and liquid contact apparatus, a housing defining a compartment, a gas inlet thereto and a downwardly-opening gas outlet therefrom; a cake of porous media within said compartment; and impeller means closing a part of said outlet and providing a support for said cake, including an inverted dome-like portion directly below said cake, being of less diameter than those of said gas outlet and said cake, and impeller blades carried by said portion.

2. In gas and liquid contact apparatus, a housing defining a compartment, a gas inlet thereto and a downwardly-opening gas outlet therefrom; a cake of porous media within said compartment; and impeller means closing a part of said outlet and providing a support for said cake, including an inverted dome-like portion directly below said cake, being of less diameter than

those of said gas outlet and said cake, and impeller blades below and carried by said portion.

3. In gas and liquid contact apparatus, a housing defining a compartment, a gas inlet thereto and a downwardly-opening gas outlet therefrom; a cake of porous media within said compartment; and impeller means closing a part of said outlet and providing a support for said cake, including an inverted dome-like portion directly below said cake, being of less diameter than those of said gas outlet and said cake, a second inverted dome-like portion below and spaced from said first portion and provided with a central opening, and impeller blades carried by said portions in the space between them.

4. In gas and liquid contact apparatus, a housing comprising a disc portion and a depending skirt portion, having a lower edge, said disc portion having a gas inlet and the lower end of said skirt portion providing a gas outlet; a cake of porous media within said housing in snug-fitting relationship with the portions thereof and extending to the horizontal plane of said edge; and impeller means closing a part of said outlet and providing a support for said cake, including a first in-

verted dome-like portion directly below said cake, a gasket upon the upper face of said first inverted dome-like portion, upon which gasket said cake rests, with portions of said cake extending outwardly of the vertical plane of the periphery of said gasket, a second inverted dome-like portion below and spaced from said first portion and provided with a central opening and a horizontally-extending peripheral flange, spaced from and facing said lower edge, and a plurality of impeller blades carried by said dome-like portions in the space between them.
